H. A. DOUGLAS.

LAMP.

FILED APR. 4, 1921.

UNITED STATES PATENT OFFICE.

HARRY A. DOUGLAS, OF BRONSON, MICHIGAN.

LAMP.

Application filed April 4, 1921. Serial No. 458,559.

To all whom it may concern:

Be it known that I, HARRY A. DOUGLAS, citizen of the United States, residing at Bronson, in the county of Branch and State of Michigan, have invented a certain new and useful Improvement in Lamps, of which the following is a full, clear, concise, and exact description.

My invention relates to enclosed lamps and is of particular service in connection with enclosed incandescent electric lamps, though the invention is not to be thus limited. In one embodiment of the invention a light transmitting lamp enclosing casing is so constructed and arranged with relation to an incandescent lamp structure enclosed thereby as to constitute an automobile fender lamp.

In carrying out my invention the light transmitting lamp enclosing casing has a portion, preferably the base portion, with which the lamp structure is separably assembled, this lamp structure being preferably provided with an upwardly projecting extension which is accessible from the top of the casing to enable the separation of the lamp structure and its casing. After the lamp structure is uncoupled it may be withdrawn through an opening that is preferably provided in the top portion of said casing.

I will explain my invention fully by reference to the accompanying drawing in which Fig. 1 is a view, mainly in sectional elevation, of the preferred embodiment of the invention; Fig. 2 is a view taken generally on line 2-2 of Fig. 1; Fig. 3 is a view, partially in section and partially in elevation, illustrating a part of a modified incandescent lamp structure; and Fig. 4 is a sectional view on line 4-4 of Fig. 3.

Like parts are indicated by similar characters of reference throughout the different figures.

The lamp structure shown, which is enclosed in accordance with my invention, is inclusive of a lamp mounting that is preferably a cylindrical metallic shell 1 having a contact carrier 2 assembled therewith within the bore thereof in any suitable way or by any suitable means as, for example, the outwardly spring pressed assembling pin 3 carried by said contact carrier and engaging a registering opening in said shell.

In the structure of Figs. 1 and 2 two fixed

contacts 4 are assembled with said carrier and are engageable at their lower ends by upwardly spring pressed contacts 5 provided upon an insulating plug 6 separably assembled with and within the enclosing casing as will more fully hereinafter appear. This plug carries two terminals 7 with which the circuit wires 8 are connected, these terminals being hollow at their upper ends to receive the lower portions of the contacts 5 and to contain the springs 9 which press the contacts 5 upwardly into engagement with the contacts 4. These latter contacts 4 are hollow in their upper portions to receive the lower portions of the contacts 10 and to receive the springs 11 that press the contacts 10 upwardly against the contacts 12, 13 which are upon the bottom of the base 14' of the incandescent lamp bulb 14. This incandescent lamp bulb base is provided with bayonet projections 15 separably received within bayonet channels 16 formed in the shell 1.

The lamp structure shown in Figs. 3 and 4 is generally similar to that shown in Figs. 1 and 2, but modified to constitute a so-called "single pole" lamp, similar parts being given similar characters of reference. In Fig. 3 the metallic shell 1 is in grounded connection with one terminal of the source of current and engages a metallic plate 17, that replaces one of the contacts 4, and also engages the metallic sheath upon the lamp base 14', this sheath constituting one terminal of the incandescent lamp filament. The other terminal 13 of the incandescent lamp filament engages the single and centrally located contact 10' that projects from the metallic spring barrel 4' connected with a contact 4" positioned to be engaged by one of the contacts 5.

In both forms of lamp structure illustrated, the metallic shell 1 is provided with bayonet channels 18 each having two seats 19, 20 to receive bayonet projections 21 carried by the casing and preferably the tubular base portion 22 of the casing 23, these bayonet projections extending laterally into the bore of such tubular base. The upwardly pressing springs 9 maintain the shell 1 in assembly with said pins and thereby in assembly with the lamp casing 23, these springs being positioned by the plug 6 held in assembly with the base of the lamp casing by the threaded annular cap 24 that

forces the plug shoulder 25 permanently against a casing shoulder 26. By suitably turning the shell the set of seats 19 and the set of seats 20 may replace each other in engagement with the bayonet projections 21 whereby the lamp may be switched into and out of circuit. Said shell may also be so turned or positioned that the longitudinal portions of the bayonet channels may be brought into register with the bayonet projections 21 to permit longitudinal movement of the shell to remove or insert the lamp structure. The lamp casing is provided with an opening through which the shell 15 may be manipulated and the lamp structure withdrawn or inserted. This opening is desirably the bore of the tubular top casing continuation 27 that is co-axial with the shell 1, the bore being sufficiently large to permit of the passage of the lamp structure therethrough. This opening in the lamp casing is provided with a closure cap 28 formed with an annular groove 29 in which said tubular continuation is slidably received. The shell 1 has an upward extension or yoke 30 which is united with said cap. By suitably pressing upon and turning the cap the shell is turned to switch the lamp into or out of circuit. If the cap be turned sufficiently to bring the longitudinal portions of the bayonet channels 18 into register with the bayonet projections 21, the cap may be lifted to remove the lamp structure which was inserted by a reversal of the movements necessary to effect its removal.

The light is emitted through the openings in the yoke 30 and suitable light transmitting openings in the lamp casing. In the form of the invention illustrated glass lenses 40 31 are provided in the lamp casing on diametrically opposite sides of the lamp bulb 14, the balance of the lamp casing being opaque. A lamp thus equipped is limited to the passage of light in two opposite directions to adapt it for use as a fender lamp. Any suitable means may be employed for assembling the lamp casing with the fender 32 or other mounting. The means shown includes an annular nut 33 threaded upon 45 the exterior of the lamp base and serving to clamp the mounting 32 and a rubber gasket 34 between the nut and the shoulder 35 upon the lamp casing. When the device is used upon a fender, one lens 31 is uncolored and faces forwardly, and the other lens is colored red and faces rearwardly.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. The combination with a light transmitting lamp casing having an opening therein; of a shell that may be passed through said opening and which may be turned, said casing and shell being in bayonet projection and channel engagement apart from said opening through which the shell may be adjusted, the channel formation having two bayonet seats to hold the shell in either of two positions to which it may be turned; an electric lamp carried by the shell and enclosed by said casing; complemental contacts one being connected with the lighting element of the lamp and the other being carried by the casing, these contacts being engaged or separated according to the position into which said shell is turned; and a closure for the opening in the casing and connected with the shell.

2. The combination with a light transmitting lamp casing having an opening therein; of a mounting that may be passed through said opening and which may be turned, said casing and mounting being in bayonet projection and channel engagement apart from said opening through which the mounting may be adjusted, the channel formation having two bayonet seats to hold the mounting in either of two positions to which it may be turned; an electric lamp carried by the mounting and enclosed by said casing; complemental contacts one being connected with the lighting element of the lamp and the other being carried by the casing, these contacts being engaged or separated according to the position into which said mounting is turned; and a closure for the opening in the casing and connected with the mounting.

3. The combination with a light transmitting lamp casing having an opening therein; of a shell that may be passed through said opening and enclosed by the casing and which may be turned, said casing and shell being in bayonet projection and channel engagement apart from said opening through which the shell may be adjusted, the channel formation having two bayonet seats to hold the shell in either of two positions to which it may be turned; an electric lamp carried by the shell and enclosed by said casing; and complemental contacts one being connected with the lighting element of the lamp and the other being carried by the casing, these contacts being engaged or separated according to the position into which said shell is turned.

4. The combination with a light transmitting lamp casing having an opening therein; of a mounting that may be passed through said opening and enclosed by the casing and which may be turned, said casing and mounting being in bayonet projection and channel engagement apart from said opening through which the mounting may be ad-

justed, the channel formation having two bayonet seats to hold the mounting in either of two positions to which it may be turned; an electric lamp carried by the mounting and enclosed by said casing; and complementary contacts one being connected with the lighting element of the lamp and the other being carried by the casing, these contacts being engaged or separated according to the position into which said mounting is turned. ¹⁰ In witness whereof, I hereunto subscribe my name this 30th day of March A. D., 1921.

HARRY A. DOUGLAS.
